[57] CLAIM

The ornamental design for a skin holder for injections,
as shown and described.

DESCRIPTION

FIG. 1 is a perspective view of a skin holder for injections embodying the design of the present invention;

FIG. 2 is a front end elevational view thereof;

FIG. 3 is a rear end elevational view thereof;

FIG. 4 is a side elevational view thereof, the side opposite being a mirror image of the side shown in FIG. 4;
and,

FIG. 5 is a top plan view thereof, the bottom being a
mirror image of the top shown in FIG. 5.

FIG. 1

FIG. 3

FIG. 2

FIG. 5

FIG. 4
